(57) **CLAIM**

The ornamental design for a bait a worm fishhook, as shown and described.

DESCRIPTION

FIG. 1 is a side elevation view of a bait a worm fishhook showing my new design;

FIG. 2 is a rear elevation view thereof;

FIG. 3 is a top plan view thereof; and,

FIG. 4 is a perspective view thereof.

The broken lines depict environmental structure and are included for illustration only and form no part of the claimed design.
